UNITED STATES PATENT OFFICE

ALFRED BAER, OF BERLIN, GERMANY

PACKING FOR THE ROTARY VALVES OF INTERNAL COMBUSTION ENGINES

Application filed September 18, 1928, Serial No. 306,640, and in Germany September 19, 1927.

This invention relates to an improved packing for the rotary valves of internal combustion engines. As is known the chief difficulty in using rotary valves for internal combustion engines lies in the fact that it is impossible owing to the high temperature to which said valves are exposed when in operation to fit the valves in such a gas tight manner as is possible in the case of steam engines, particular difficulty existing in designs in which the rotary valves are located in the cylinder head.

It is necessary that the diameter of the valve whilst cold shall be somewhat smaller than the diameter of the bore or housing in which it is to operate so that in operation the valve can expand when heated and effect proper operation in this state. Such rotary valves, however, owing to the unfavourable working conditions are subject to very heavy wear and it is found to be impossible to keep even excellently fitted valves gas tight for any length of time. This lack of tightness involves loss of energy and, therefore, the fitting of rotary valves in fixed bores or housings has been practically discontinued, said rotary valves being now fitted in housings comprising two mutually movable halves, which can be so adjusted towards one another by mechanical or automatic means that satisfactory working of the parts can be obtained independent of the effects of temperature or wear.

Unfortunately, the expedient suggested above introduces high working pressures and the friction on the valve becomes great with the result that a comparatively large proportion of the energy produced is absorbed in operating the valves and to overcome this difficulty it has been proposed to mount the rotary valve in roller bearings.

With such an arrangement it has been found necessary to make the parts which cooperate with the rotary valve movable in themselves and to fit each part separately to said rotary valve. Such arrangements, as is known, introduce the disadvantage that difficulty exists in maintaining a gas tight joint between the cooperating parts so that although the engine may operate satisfactorily

at a certain number of revolutions as the speed increases the performance of the engine does not increase in ratio to the number of revolutions but at a much lower rate. This defect is due to the fact that with high speeds of revolution a continually larger percentage of the products of combustion are retained in the cylinder space or in the passages leading thereto owing to ineffective joints and these products of combustion contaminate the incoming fresh gas mixture with the result that the value thereof is reduced.

This invention has particular reference to a packing for rotary valves of the type hereinbefore referred to and avoids the difficulties indicated, thus making it possible to effect, at all times, a proper gas tight joint between a rotary valve having a fixed bearing and the parts cooperating therewith both at the inlet as well as the exhaust ports.

Further, the improved construction provides that the rotary valve shall require less energy to drive it than has been possible in known arrangements inasmuch as the pressure of the cooperating parts with the rotary valve is considerably relieved and the highly objectionable seizing of the cooperating surfaces entirely obviated.

An especial advantage of the invention resides in the fact that owing to the satisfactory packing arrangements all loss of fresh gas mixture and, at the same time, any contamination of the same by exhaust products is absolutely avoided.

In the drawings:—

Figure 1 is a sectional elevation of part of an internal combustion engine;

Figure 2 is a side elevation of the construction illustrated in Figure 1, the view being taken on the line 2—2 of Figure 1;

Figure 3 is a detail sectional view through the lower part of the cylinder head and rotary valve as illustrated in Figure 1 but to an enlarged scale;

Figure 4 is a sectional elevation of the improved rotary valve;

Figure 5 is a fragmentary view showing in side elevation a part of the improved rotary valve;

Figure 6 is a plan view of the movable part of the cylinder head;

Figure 7 is a plan view of the flexible packing element for the movable part of the cylinder head;

5 Figure 8 is a side sectional elevation of Figure 7 taken on the line 8—8 thereof and looking in the direction of the arrow;

10 Figure 9 is a sectional elevation of one of the upper packing shoes;

Figure 10 is a plan view of the packing shoe illustrated in Figure 9;

15 Figure 11 is an end elevation of the packing shoe illustrated in Figure 9 looking in the direction of the arrow and showing in elevation the jointing element;

Figure 12 illustrates in sectional elevation an alternative construction.

20 As illustrated in the drawings, 1 indicates the cylinder, 2 the piston, 3 the cooling jacket of the cylinder and 4 a cylinder head extending over the whole of the cylinder block, said cylinder head being jointed to the cylinder block by means of the packing plates 5. Rotary valves 6, 6' . . . are arranged in bores 25 in the cylinder heads 4, said valves being combined in pairs for each two cylinders and supported in the ball bearings 7. The contacting parts between each two rotary valve parts 6, 30 6' . . . as illustrated in Figure 2 are kept coaxial by aligning rings 7' and are united into a whole by the pins 8. Adequate play is provided between the rotary valves 6, 6' . . . and the corresponding bore of the cylinder head 35 said rotary valves being formed hollow and each having two diametrically opposite openings 9 in the circumference and an open ended passage 10 which passes across the valve.

Both the openings 9 and the openings of 40 the passages 10 serve as ports for the inlet of the fresh gas and the discharge of the exhaust gases.

45 A packing piece 11 is arranged in the lower part of each cylinder head 4 and opposite the rotary valve 6, 6' . . . as is clearly shown in Figure 3 said packing piece forming the top cover of the cylinder and having openings 9' and 10' (see Figure 6), which cooperate with the corresponding openings of the rotary 50 valve. The packing piece 11 is movable axially and is retained in position by a diaphragm 12 (Figures 3, 7 and 8) which may be of nickel and which is initially stressed so that the packing piece 11 is always pressed against 55 the surface of the valve with a certain pressure.

As will be seen, the diaphragm 12 consists of a ring of sheet metal, say nickel, having a circular raised bead 12' pressed therefrom, 60 the flange like portions of the ring provided on both sides of the circular raised bead 12' serving to retain the diaphragm 12 in place. The inside flange is fixed to the packing piece 11 by means of the screwed ring 13, whilst the 65 outer flange is pressed by the screwed ring

14 against an abutment surface in the cylinder head (see Figure 3) so that the packing piece 11 shall be axially movable to the extent of the elasticity of the diaphragm 12, said packing piece 11 being pressed against the rotary valve by the pressure in the cylinder 70 when the pressure in the cylinder produces a force on the piece 11 which exceeds the force exerted by the diaphragm.

Packing shoes 15 and 15' are arranged 75 in the upper part of the cylinder head 4, opposite the openings 9 and 10 of the rotary valve as illustrated in Figures 1, 9, 10 and 11. Each of these shoes consists of a part 16 which fits to the circumference of the rotary valves and an inlet conduit 17 (see Figure 9) an axially arranged projection or shoulder 18 serving as a bearing surface for the pressure spring 20 arranged in a special guide 19 in the cylinder head 4. A circular raised or 80 beaded portion 21 is arranged on the free end of the conduit 17 and has a jointing diaphragm 22 similar to the jointing diaphragm 12 pressed thereon by means of the flange of the suction piping 23 or exhaust piping. 90

The device operates as follows:

During the suction stroke a reduced pressure exists in the cylinder 1 and the operative parts will be in the position shown in Figure 1 thus allowing fresh gas to be received from the suction piping 23 through the hollow rotary valve 6 into the cylinder 1, the flow of fresh gas into the interior being unobstructed. During the compression and expansion strokes which now follow, the 100 rotary valve 6 turns in the direction of the hands of a watch, so that at the moment when the exhaust stroke begins the passage 10 is in a vertical position and the opening of the passage 10 is opposite the opening 10' (see 105 Figure 6) in the packing piece 11. Owing to the pressure in the cylinder the packing piece 11 is pressed against the rotary valve 6 so that the exhaust of the products of combustion is effected without leakage it being 110 impossible for any products of combustion to escape laterally. This is ensured, firstly, by the fact that the surface of the packing piece 11 is tightly pressed against the peripheral surface of the rotary valve 6 and the presence of the diaphragm 12, which completely closes the annular space between the packing piece 11 and the aperture in the cylinder head 4 surrounding it, so that no gases 115 of combustion can remain in this space and secondly by the fact that the products are carried off straight away through the passage 10 into the packing shoe 15' opposite same and then, as will be seen from Figure 1, laterally to the left into the exhaust pipe. The springs 20 ensure that the shoes 15 and 15', resting on the upper part of the rotary valve, are kept gas tight, the tension of the springs 20 being so adjusted that only as 120 much pressure is exerted on the packing.

shoes as is absolutely necessary to prevent any lifting of the packing shoes.

As the rotary valve is a loose fit in the bore therefor all unnecessary resistance is avoided. During the compression, expansion and exhaust periods the packing piece 11 is pressed against the circumference of the rotary valve, said rotary valve being actuated from the main shaft of the engine in any well known and convenient manner.

In the example illustrated in Figures 12 and 13 owing to the special provision for cooling exceptional advantages are obtained.

Experience has shown that although the construction and arrangement hereinbefore described effectively fulfils its purpose in a general way, when operation for lengthy periods is essential difficulties arise owing to the effect of the high temperature upon the elasticity of the packing ring, said elasticity being found to somewhat diminish. There is a further difficulty that the oil necessary for lubricating the various operative surfaces exposed to friction is adversely affected by the temperature which exists and which has as its result a reduction in the lubricating power of the oil.

The valve is continually cooled by a flow of cooling medium therethrough, the internal cooling arrangements preventing excessive heating of the parts and, at the same time, serving to conduct as much heat as possible from the cylinder end. A further advantage of the alternative arrangement is illustrated in Fig. 12 which presents the additional advantage that by means of a supplemental packing arrangement the actual packing is excluded from the intensest heat in the combustion space. To reduce the pressure on the packing piece 11 as much as possible spring loaded levers engaging with said packing piece have been provided in order that the packing piece shall be relieved of all injurious and unnecessary strain to such an extent that it shall be possible for it to give satisfactory service even under the most unfavourable conditions.

In the alternative construction illustrated, the rotary valve 6 is located within a housing 4 formed as a cylinder head, said rotary valve being provided with two passages 9 and 10 which permit of the admission of fresh mixture and the discharge of exhaust gases respectively.

A movable packing piece 11 is arranged between the cylinder and the rotary valve 6, said packing piece being jointed with the cylinder in a gas tight, although flexible, manner by means of the diaphragm 12, the inner flange part of which is connected to the packing piece 11 whilst the other flange of the diaphragm 12 is engaged with the cylinder head by means of the collar 14.

To prevent the hot cylinder gases from passing through the annular space 23 be-

tween the rings 13 and 14, attacking the diaphragm 12 and injuriously heating it, a packing ring 24 is arranged in a groove externally arranged on the screwed ring 13, said joint ring elastically engaging with the internal bore of the ring 14 so as to isolate the space 23 in a permanent and reliable manner thus enabling the diaphragm 12 to be uninfluenced by the hot cylinder gases.

To prevent the diaphragm 12 taking a permanent set owing to the continuous loading thereof by the weight of the packing piece 11 and the pressure due to the operation of the piston during the suction stroke and the following pressure owing to the compression, radial bores 25 are arranged in the cylinder head, each of said bores being provided with a double armed lever 26, 27 one of the ends of each of said levers engaging in a corresponding recess in the packing piece 11 whilst the other free end of each of said levers is loaded by means of compression springs 28 in such manner that the packing piece 11 is permanently pressed against the circumference of the rotary valve 6. For the purpose of facilitating the fitting of the levers 26 and 27 they are conveniently given the slender, tapered shape illustrated in Figure 12 which offers the advantage that the levers 26 and 27 lie at the bottom of the bores 25 with their rounded off shoulders acting as a fulcrum thus obviating the necessity for any special bearings. Externally, the recesses 25 are closed by means of plates 29.

Proper contact between the rotary valve and the packing piece 11, alternatively, may be effected by means of spring loaded draw rods operating from above, spring loaded pressure pins operating from below, or by any spring devices operating in an equivalent manner.

The cooling of the rotary valve is effected in a manner described and claimed in a divisional application identified by Serial Number 514,683, filed Feb. 6, 1931.

Further, it will be seen that owing to the supplemental packing ring 24 access by the hot cylinder gases to the diaphragm 12 is prevented thereby obviating any possibility of the diaphragm 12 being directly effected by such hot cylinder gases.

Obviously, the invention may be put into effect in a variety of ways and those described and illustrated must be considered to be by way of example only.

I claim:—

1. Improved packing for the rotary valves of internal combustion engines of the type specified, said improved packing comprising, a movable part cooperating with the surface of the valve, a stressed elastic annular diaphragm clamped by the inner periphery thereof to said movable part, and means clamping the outer periphery of the dia-

phragm to the cylinder head so as to prevent the leakage of gases from the cylinder.

2. Improved packing for the rotary valves of internal combustion engines of the type specified, said improved packing comprising a stressed elastic annular diaphragm of sheet metal with a bead of semi-circular profile pressed therein between the inner and outer peripheries thereof; the inner periphery of each of said packing rings being clamped against an abutment on the movable part cooperating with the surface of the valve, and the outer periphery of each of said packing rings being clamped against an abutment in the cylinder head so as to prevent the escape of gases from the cylinder.

3. Improved packing for the rotary valves of internal combustion engines of the type specified, said improved packing comprising a stressed elastic annular diaphragm of sheet metal with a bead of semi-circular profile pressed therein between the inner and outer peripheries thereof; the inner periphery of each of said packing rings being clamped against an abutment on the movable part cooperating with the surface of the valve, the outer periphery of each of said packing rings being clamped against an abutment in the cylinder head so as to prevent the escape of gases from the cylinder; an opening in said movable part for cooperating with the inlet opening in the valve to allow of the admission of gas mixture to the cylinder; an opening in said movable part for cooperating with the exhaust opening in the valve to allow of the discharge of the products of combustion from the cylinder and parts cooperating with said valve for supplying gas mixture to and receiving products of combustion from said valve.

4. Improved packing for the rotary valves of internal combustion engines of the type specified, said improved packing comprising a stressed elastic annular diaphragm of sheet metal with a bead of semi-circular profile pressed therein between the inner and outer peripheries thereof; the inner periphery of each of said packing rings being clamped against an abutment on the movable part cooperating with the surface of the valve, the outer periphery of each of said packing rings being clamped against an abutment in the cylinder head so as to prevent the escape of gases from the cylinder; an opening in said movable part for cooperating with the inlet opening in the valve to allow of the admission of gas mixture to the cylinder; an opening in said movable part for cooperating with the exhaust opening in the valve to allow of the discharge of the products of combustion from the cylinder; a hollow shoe located on the surface of the rotary valve for cooperating with the inlet opening in the valve, a second hollow shoe located on the surface of the rotary valve for cooperating with the

exhaust opening in the valve and springs for maintaining the shoes in position.

5. Improved packing for the rotary valves of internal combustion engines of the type specified, said improved packing comprising a stressed elastic annular diaphragm of sheet metal with a bead of semi-circular profile pressed therein between the inner and outer peripheries thereof; the inner periphery of each of said packing rings being clamped against an abutment on the movable part cooperating with the surface of the valve, the outer periphery of each of said packing rings being clamped against an abutment in the cylinder head; a groove in the clamping means for the inner periphery; and additional packing means constituted by a spring jointing ring in said groove for cooperating with the surface of the clamping means for the outer periphery so as to prevent the cylinder gases from impinging on the diaphragm or escaping from the cylinder.

6. Improved packing for the rotary valves of internal combustion engines of the type specified, said improved packing comprising a stressed elastic annular diaphragm of sheet metal with a bead of semi-circular profile pressed therein between the inner and outer peripheries thereof; the inner periphery of each of said packing rings being clamped against an abutment on the movable part cooperating with the surface of the valve; the outer periphery of each of said packing rings being clamped against an abutment in the cylinder head so as to prevent the escape of gases from the cylinder; an opening in said movable part for cooperating with the inlet opening in the valve to allow of the admission of gas mixture to the cylinder; an opening in said movable part for cooperating with the exhaust opening in the valve to allow of the discharge of the products of combustion from the cylinder and parts cooperating with said valve for supplying gas mixture to and receiving products of combustion from said valve; means for preventing the cylinder gases from impinging on the diaphragm or escaping from the cylinder; means for cooling said rotary valve; a plurality of levers engaging by one end with said movable part; springs for engaging the free ends of each of the levers so as to press the movable part into contact with the surface of the valve and counter-act the effect due to the suction of the engine.

7. Improved packing for the rotary valves of internal combustion engines of the type specified, said improved packing comprising a stressed elastic annular diaphragm of sheet metal with a bead of semi-circular profile pressed therein between the inner and outer peripheries thereof; the inner periphery of each of said packing rings being clamped against an abutment on the movable part cooperating with the surface of the valve; the

outer periphery of each of said packing rings being clamped against an abutment in the cylinder head so as to prevent the escape of gases from the cylinder; an opening in said movable part for cooperating with the inlet opening in the valve to allow of the admission of gas mixture to the cylinder; an opening in said movable part for cooperating with the exhaust opening in the valve to allow of the discharge of the products of combustion from the cylinder and parts cooperating with said valve for supplying gas mixture to and receiving products of combustion from said valve; means for preventing the cylinder gases from impinging on the diaphragm or escaping from the cylinder; means for cooling said rotary valve; a plurality of radially disposed bores in the cylinder head; a two armed lever arranged in each bore and having a part thereof arranged to operate as a fulcrum; the inner ends of said levers engaging with the movable part whilst the outer ends of said levers are spring pressed so as to press the movable part into contact with the surface of the valve and counter-act the effect due to the suction in the engine.
